LAMP

Everett L. Crews, 302 Bercliff Drive,
South Bend, Ind. 46615

Filed Dec. 10, 1970, Ser. No. 26,399

Term of patent 7 years

Int. Cl. D26—05

U.S. Cl. D48—20

Fig. 1

Fig. 2

Fig. 3

FIG. 1 is a perspective view of a lamp showing my new design;

FIG. 2 is an enlarged side elevational view thereof, the lamp being fragmentarily shown for convenience of illustration;

FIG. 3 is a cross-sectional view taken on line 3—3 of FIG. 2.

I claim:

The ornamental design for a lamp, as shown and described.
